19 Claims. (Cl. 63—1)

1

This invention relates to bracelets and similar articles of adornment ordinarily worn on the arm. The invention particularly relates to bracelets which when in position embracing the arm are more or less rigid or have certain rigid parts.

Bracelets and similar articles of adornment have been made heretofore of generally annular form as complete circlets through which the hand may be pressed or with a gap or opening in the annulus through which to pass the wrist. Many mechanical designs have also been proposed in which the annulus is made with parts which are in hinged relation to open a gap therein or to enlarge the area enclosed by the annulus through which the hand may be passed. The parts of the bracelet which thus are moved apart are brought together again to provide the proper embracing form and size with respect to the wrist or the arm. Various other types of bracelets have been proposed with mechanical devices for holding the bracelet in such embracing form.

For additional adornment and for convenience of the wearer, frequently a handkerchief is tucked at the wrist within the end of the sleeve of the dress or beneath a bracelet of conventional form. As there is no provision in such conventional bracelets or in the dress for attaching the handkerchief, it is easily displaced in the movements of the arm or hands and may be lost. In some cases also with conventional bracelets, the character of the decoration thereon or the jewels set therein, especially along the edges thereof, may tear the handkerchief upon insertion under or removal thereof from beneath the bracelet. Moreover, the space between the wrist and the bracelet itself may in some cases be too small for comfortable insertion of the handkerchief between the wrist and the bracelet and in other cases may be too large to insure that the handkerchief be retained in its place.

It is an object of the invention to provide in a bracelet, especially one to be worn on the arm, means for attaching a handkerchief to the bracelet in an artistic manner.

It is another object of the invention to provide in a bracelet attachment means such that the handkerchief readily may be brought into engagement with this means and may be removed therefrom when desired without danger of damage to the handkerchief.

It is a further object of the invention to provide in a bracelet a space within which the handkerchief may be at least partially drawn when engaged by such attachment means, the decorated

2

portion of the handkerchief depending artistically from the bracelet.

A still further object of the invention is to provide for concealment of the handkerchief-holding means and to prevent said holding means from catching in the clothing while providing for securely attaching the handkerchief to the bracelet.

It is an additional object of the invention to provide in a bracelet means for attaching a handkerchief thereto associated with a compact or similar receptacle.

The bracelet of the invention broadly comprises a part of such form that it may extend about or embrace the arm of the wearer to hold the bracelet thereon and means carried by said part adapted to engage a handkerchief to attach the handkerchief to the bracelet.

In one of its aspects the bracelet of the invention comprises a part for extending about the arm of the wearer and a part which is supported by the first part so that said parts may be moved slidably with respect to each other. Ordinarily one of these parts will be of annular or arcuate form to extend about or embrace the arm. In order to hold the handkerchief attached to the bracelet for the purposes which have been described, a means is provided which cooperates with at least one of the parts to hold the handkerchief attached to the bracelet when the parts are slidably moved in a predetermined relation to each other, preferably circumferentially of the annular part.

In another aspect the bracelet of the invention comprises a pair of annular parts for extending about the arm which are held together in side-by-side relation but which are capable of being moved apart so that the handkerchief may be inserted therebetween.

The means for holding the handkerchief may be a clip preferably made with a ball end rounded and smooth to prevent tearing or other damage to the handkerchief. This clip may be carried either by the annular part, such as usually constitutes the main structure of the bracelet of conventional form, or it may be carried by a member which is slidable relative to said annular part. This member may be slidable on a segment which is supported in fixed relation to and exteriorly of the annular part of the bracelet and generally parallel thereto circumferentially thereof. This segment may be of arcuate form corresponding to the arcuate form of the annular part of the bracelet or it may be of other contour, for example, the flat bottom of a compact box which is in parallel relation to a planar or sub-

stantially planar portion of the annular part of the bracelet.

The segment positioned exteriorly of the annular part of the bracelet may form with said annular part a space within which the handkerchief-engaging clip may move, this clip being carried by the member which is slidable on the segment. As this member and clip are slidably moved along the segment, the handkerchief brought into engagement with the clip may be drawn to the desired extent into the space between the segment and the annular part of the bracelet. The fold of the handkerchief, for example, may be tucked under the clip and drawn into the space by movement of the clip along the segment, leaving the corner portions of the handkerchief exposed and depending from the bracelet in an artistic manner.

When the clip is attached to the annular part, a segmental member may be provided of such form as to be slidable circumferentially of the annular part of the bracelet, thereby to pass over the clip and to cover a portion of the handkerchief which is held by the clip. In these sliding movements of the clip-carrying member on the fixed segment or of the slidable segmental member, means such as a spring piece may be brought into operation for pressing the clip upon the handkerchief and against the annular part of the bracelet or against another cooperating part which aids securely to hold the handkerchief attached to the bracelet.

The segments or segmental members above referred to, whether in fixed relation to the annular part of the bracelet or in slidable relation thereto, may provide a space open at one or both ends for passage of the clip into and out of said space, preferably in the direction circumferentially of the annular part of the bracelet, so that the handkerchief may be drawn into said space and may be drawn out of said space by reverse movement of the clip therein. This space may be otherwise completely enclosed or may be open at its sides. Preferably, however, the segment provides a cover for the space which extends in the circumferential direction generally parallel to the annular part of the bracelet so as to prevent catching of the clip and the spring piece and to conceal the fold of the handkerchief.

Other objects and features of the invention will be understood from the following description of the drawings in which:

Fig. 1 is a perspective view and Fig. 2 is an end view of a circular bracelet with a slidable segmental member and with the clip attached to the annular part of the bracelet;

Fig. 3 is an end view similar to Fig. 2 but with the annular part rotated with respect to the segmental member to draw the handkerchief within the space between the annular part and the segmental member;

Fig. 4 is a perspective view of a modification of the invention in which the clip is slidable on a fixed segment;

Fig. 5 shows another modification in which the clip is slidable on the segment;

Fig. 6 shows an end view of the bracelet of Fig. 4;

Fig. 7 shows an end view of the bracelet of Fig. 4 with the handkerchief drawn into the space by movement of the clip along the segment;

Fig. 8 shows a modification of the invention in which the bracelet as a one piece band provides the annular part, the segment and the clip

slidable in the annular space between the band and the segment;

Fig. 9 is a perspective view of the bracelet of Fig. 8 with the clip removed from the annular space;

Fig. 10 is an end view of the bracelet of Fig. 8 showing the handkerchief engaged by the clip;

Fig. 11 is a perspective view of another modification of the invention which includes a compact in combination with the bracelet;

Fig. 12 shows the parts of Fig. 11 separated for the purpose of placing the bracelet on the arm;

Fig. 13 is a fractional elevation of the upper portion of the bracelet of Fig. 11, the compact lid being closed, with the clip in position to receive the handkerchief;

Fig. 14 is similar to Fig. 13 but shows the handkerchief in place, certain parts being broken away;

Fig. 15 is a section taken on line 15—15 of Fig. 13;

Fig. 16 is a perspective view of another modification of the invention;

Fig. 17 is a perspective view showing a bracelet embodying a still different form of the invention; and

Fig. 18 shows a perspective view of an embodiment of the invention in combination with a belt.

In Figs. 1, 2 and 3 the bracelet 1 is in the form of a continuous circular band 3 of substantial width, that is, the vertical dimension in Fig. 1. The diameter of the annulus of the band 3 is such that the hand may be pressed through the circular opening to leave the bracelet loosely on the wrist but to prevent it from readily falling therefrom. Attached to the band 3 exteriorly thereof is a spring piece 7, shown in Figs. 1 and 2 in position sprung away from the exterior surface of the annular part or band 3. A clip 5 is fastened upon this spring piece at the face thereof toward the band 3. When the spring piece 7 is pressed inwardly toward the band 3, the ball end 9 of the clip 5 is pressed into contact with the exterior surface of the band 3. A handkerchief may be placed beneath said ball end 9 of the clip 5 and, when pressure is brought on the spring piece 7, will be held between the ball 5 and the exterior surface of the band 3.

In order to bring pressure upon the spring piece 7, as well as to cover a portion of the handkerchief, upon the annular band 3 is supported the segmental member 10 having a segment 11 exterior to the annular part or band 3. This segment 11 extends circumferentially of the band 3 for a portion of the extent of said band. In the particular embodiment of the segmental member 10 shown in Figs. 1, 2 and 3, adjacent the inner surface of the band 3 an additional segment 13 is arranged parallel to said band and to said segment 11. The segments 11 and 13 are connected adjacent both edges of the band 3 by connecting webs 15 spaced apart circumferentially of the annular part or band 3 and of the segments 11 and 13. The webs 15 which are at the lower edge of the band 3 in Fig. 1 are not visible but are similarly arranged as those shown adjacent the upper edge of annular part 3. These webs hold the segment 11 in spaced relation to the segment 13, the segment 13 preferably conforming closely to the inner surface of the band 3 to provide substantially a continuous inner surface for contact with the arm.

The space between the outer surface of the annular part or band 3 and the inner surface of segment 11 is such that a substantial portion of

the handkerchief may be disposed between said surfaces as shown in Fig. 3. This is accomplished as above mentioned by placing the handkerchief, preferably a folded portion thereof, under the ball 9 of the clip 5. Upon slidably moving the member 10, which comprises the segments 11 and 13, circumferentially of the annular part of band 3, first the end edge of the segment 11 and thereafter the inner surface thereof are brought into contact with the spring piece 7 to press the spring piece inwardly toward the band 3. As will be seen in Fig. 3, this spring piece 7 holds the clip 5 in contact with the handkerchief and presses it against the outer surface of the band 3. The segmental member 10 in the sliding movement thereof covers a portion of the handkerchief while maintaining pressure of the clip thereon.

It will be apparent that the spring piece 7 also is effective to hold the segmental member 10 outwardly with respect to the annular part or band 3 so that the segment 13 is in contact with the inner surface of the band 3. It will also be understood that the disposition of the handkerchief within the space between the segment 11 and the outer surface of the band 3 may be brought about by either holding the band 3 stationary and moving the segmental member 10 thereon or this member 10 may be held and the annular part or band 3 moved relative thereto. In either case the handkerchief engaged by the clip will be brought within the intervening space so that a portion thereof will be covered by the segment 11.

When it is desired to remove the handkerchief, reverse movement of the segmental member 10 and the band 3 with respect to each other uncovers the handkerchief and the clip. Release of the pressure of the segment 11 on the spring piece 7 releases the clip from the handkerchief so that it then may be removed. The handkerchief is protected by the segment 11 and the clip 9 and spring piece 7 also are covered so that these holding devices may not catch in the clothing. The segmental member 10 may be made with smooth surfaces and rounded corners and edges or otherwise finished as is usual with jewelry and ornaments of this type.

In Figs. 4, 6 and 7 is shown a bracelet of conventional form with a gap or opening in the annular part 20 so that the narrow dimension of the wrist may be passed through this opening. The annular part 20 is in the form of a band tapering from its central portion toward the ends 21 which are spaced apart to provide the gap. Adjacent the central portion of the annular part 20 and fastened thereto in the particular embodiment of Figs. 4, 6 and 7 by means of webs 23 is a segment 25 spaced from the annular part 20 exteriorly thereof and in generally parallel relation thereto circumferentially thereof. The space 24 between the segment 25 and the annular part or band 20, as may be seen in Figs. 4, 6 and 7, is open at the sides but the segment 25 provides a cover for said space extending generally circumferentially of the annular part.

Slidably supported on the segment 25 is a member 27 carrying clip 29 having ball end 30 for engagement with the handkerchief as shown in Fig. 7. A spring piece 31 also attached to the member 27 is adapted to engage the inner surface of the segment 25 as the member 27 is moved therealong and to press the clip 29 inwardly toward the annular part 20 and into contact with the handkerchief inserted beneath the ball end of the clip. The handkerchief may be placed beneath the ball end 30 when the member 27 and

the clip 29 are in the position shown in Figs. 4 and 6. When the member 27 is moved along the segment 25 upwardly to the position shown in Fig. 7, the spring piece 31 slides under the segment 25 and the handkerchief is drawn by the clip 29 and its ball end 30 into the space 24 between the segment 25 and the annular part 20. The segment 25 thus protects the handkerchief and covers the clip 29 and its spring piece 31 to prevent catching as above mentioned and cooperates with the spring piece and clip securely to hold the handkerchief in place with the decorated portions thereof exposed. Upon return sliding movement of the member 27 to the position shown in Fig. 6, the clip is released by removal of the pressure on the spring piece 31 and the handkerchief may then be removed from the bracelet.

In the modification of the invention shown in Fig. 5, the spring piece 31 is carried by a pin the head 35 of which is shown in Fig. 5. This pin extends through slot 37 formed in segment 25. The pin at its inner end may be riveted or otherwise suitably fastened to the spring piece 31 to which also the clip 29 having a ball end 30 is fastened. Movement of the pin under pressure of the finger on the head 35 along the slot 37 will effect movement of the spring piece 31 and of the clip 29 circumferentially along the space between the segment 25 and the annular part 20 in the same manner as described in connection with Figs. 4, 6 and 7. In Fig. 5 a continuous web 39 is provided in place of the several webs 23 of Figs. 4, 6 and 7 connecting the annular part 20 with the segment 25 to hold the segment in spaced relation to the annular part 20. A connecting web 39, not visible in Fig. 5, is provided at the lower edge of the annular part 20 similar to the web 39 shown in this figure at the top edge of the part 20. The annular space between the segment 25 and the annular part 20, therefore, substantially is completely closed except that this space is open at least at the end from which, as shown in the figure, the clip 29 may project for insertion and release of the handkerchief. The opposite end of this annular space may be closed if desired.

In Figs. 8, 9 and 10 is shown another modification of the invention in which the bracelet is in the form of a band 40 of flexible or bendable material which may be wrapped around the arm or other body extremity. Preferably while bendable this material is sufficiently rigid so that when in the wrapped relation the annular part 55 of the bracelet thereby formed is capable of supporting the clip in clamping relation to the band as well as providing means for fastening the band in its wrapped relation. Preferably in this embodiment adjacent one end of the band the segmental member 41, comprising the segment wall 43 and side walls 44 joining the corresponding edges of the segment 43 and the band 40, provides a space open at both ends extending lengthwise of the band. The spacing of the segment wall 43 from the band is such that the opposite end 45 of the band 40 which is retroverted to form a hook 47 is insertable in the open end 48 of the space provided by the segmental member 41 and may be passed completely through said space and then with a slight reverse movement may be hooked on the segment wall 43, as shown in Figs. 8 and 10. The band 40 in whole or in part may be of material having sufficient spring or resilient quality to bias the band to hold the open position shown in Fig. 9 and to hold

the hook 41 in engagement with the end 42 of the segmental wall 43 when the band has been wrapped upon the wrist and the end 45 inserted as described.

Adjacent the end 45 of the band and at the internal surface thereof is mounted the clip 49 beneath which a fold of the handkerchief may be placed in the relation shown in Fig. 10. This may be done after the band has been wrapped upon the wrist and the end 45 projected through and beyond the end 42 of the segmental member 41. Upon reverse movement of the end 45 of the band to engage the hook 41 with the segment wall 43, the handkerchief will be drawn somewhat into the space provided by the segmental member 41, leaving the decorated portions of the handkerchief depending from the bracelet upon the wrist. As the band 40, or at least the portion thereof adjacent the end 45, may be made of spring material, the end portion of such band may be of arcuate form as shown in Fig. 10 so that the end portion is biased into contact with the ball end 51 of the clip 49. When the end 45 of the band has been projected through the end 42 of the segmental member 41, this end 45 of the band and the ball end of the clip 49 may be separated slightly to permit insertion of the fold of the handkerchief. The spring action of the end 45 against the clip 49 holds the handkerchief as it is drawn into the space in bringing the hook 41 into holding engagement with the segmental wall 43.

Within the scope of the invention, the band 40 may be made in other forms and of materials which are flexible but to which may be attached a member functioning as does the segment wall 43 in spaced relation to the band 40 beneath which the hook end 45 may be passed to engage the edge of the segment 43 upon the reverse movement of the end 45 as described. If desired the segment wall 43 may be suitably supported to leave the sides 44 open. The portion of the band adjacent the end 45 may be only of sufficient length and of such rigidity as to provide for fastening the clip in order to hold the handkerchief as described, the main portion of the band 40 being flexible. The length of the segment wall 43 if desired may be merely sufficient to provide for engaging the hook 41. The length of the portion of the band adjacent end 45 then may be such as to provide for the desirable covering of the fold of the handkerchief and of the clip.

The clip 49 may be so formed and mounted on the end portion 52 of the band 40, in consideration also of the form or curvature and the spring quality of this end portion 52 that when the end 45 of the band is projected from the end 42 of the space within the segmental member 41 the ball end 51 of the clip 49 will separate sufficiently from end 45 of the portion 52 of the band to permit the fold of the handkerchief to be passed beneath this ball end. When the reverse movement of end 45 is effected to draw the clip and handkerchief within the space, the portion 52 being in contact with the inner surface of the segment wall 43, as shown in Fig. 10, the end 45 of the band 40 is pressed toward the ball end 51 to effect clasping of the handkerchief.

The embodiment of the invention shown in perspective in Fig. 11 includes the features which have been above described in connection with the other figures of the drawing, particularly Figs. 4, 5, 6 and 7, in combination with a receptacle such as a compact. The annular part 60

5 of the bracelet is formed in two sections 61 and 62 shown in separated relation in Fig. 12. The section 62 may be of tubular cross-section throughout its length or adjacent the ends 64 thereof to receive the ends 66 of the legs 67 of the member 61. Preferably the legs 67 are of spring material which permits spreading and straightening of the legs 67 to permit insertion of the ends 66 into the ends 64 of the tubular member 62. As the member 61 is pressed toward the member 62 with these ends so inserted, the ends 66 will follow the curve of the tubular member 62 and retain the two members 61 and 62 in the relation shown in Fig. 11 to provide the annulus of the bracelet.

20 Spanning between the legs 67 of the member 61 and mounted thereon is a receptacle 68 which may be a compact having a flat bottom 69 and side walls 70. The legs 67 of the member 61 may extend upwardly to form the end walls of the receptacle. As shown in dotted lines in Fig. 12, the end wall above the left-hand leg 67 is provided with an opening 71 through which, as shown in Fig. 13, may project the clip 73 carried by a bridge piece 75 having its ends 76 slidably engaging the side walls 70 of the receptacle. The bridge piece is formed with a part 78 passing through slots 79 in the side walls 70 and beneath the receptacle bottom 69 to connect the two ends 76 of the bridge piece 75, as shown in Fig. 15. When the bridge piece 75 is moved to the left as shown in Fig. 13 the handkerchief may be placed beneath the projecting clip 73. Upon movement of the bridge piece 75 toward the right, the clip passes over the plane wall 65 of the member 61, this wall 65 being parallel to and spaced somewhat from the bottom 69 of the receptacle to provide for movement of the part 78 of the bridge piece, the clip carried thereby and of the handkerchief engaged by the clip 73. Also carried by the bridge piece 75 is a spring piece 77 which by contact with the bottom 69 of the receptacle as the bridge piece is moved toward the right presses the clip 73 down upon the plane wall 65. Thus upon movement of the bridge piece 75 toward the right to the position shown in Fig. 14, the fold of the handkerchief placed beneath the clip is drawn into the space between the wall 65 and the bottom of the receptacle 69 leaving the decorated portion of the handkerchief depending from the opening 71. In the particular embodiment being described the ends 76 of the bridge piece 75 are turned up along and over the side walls 70, as shown in Fig. 15. The lower portions of the wall 70 are connected to the plane wall 65 of the annular part of the bracelet. Thus a rigid structure is formed supporting the receptacle and providing the desired space within which the clip may be slidably moved, while engaging the handkerchief to draw a portion thereof into this space and to hold it attached to the bracelet.

65 The ends 76 of the bridge piece 75 which are slidable on the side wall 70 of the receptacle may be so formed that the cover 81 of the receptacle may be sprung down into place, as shown in Fig. 15, to be held closed by these ends acting as clasps, the bridge piece 75 also being held against movement along the walls 70. To this 70 end if desired the side walls 70 may have a slight spring which will permit the cover to be pressed down beneath the turned over edges 76 of the bridge piece 75 as shown in Fig. 15. The cover may be hinged to the receptacle by means of a 75 hinge 83 and may be provided with a button 85

for lifting the cover 81 from the closed position, springing it past the turned over edges of the bridge piece 75.

It now will be clear that the embodiment of the invention shown in Figs. 11-15 inclusive utilizes the structure of the receptacle in cooperation with the annular part of the bracelet to provide a space for receiving the handkerchief and the clip while also supporting this clip for sliding movement thereof in a manner similar to that shown in Figs. 4, 6 and 7. The bottom of the receptacle serves the purpose of the segment 25, for example, of Figs. 4, 6 and 7 in pressing the clip 73 into contact with the handkerchief by the action of the spring piece 77. By lifting the cover slightly, the bridge piece may be slidably moved along the side walls 70 to insert or remove the handkerchief and this may be readily accomplished while the bracelet carrying the receptacle embraces the wrist. The construction may be modified to permit the cover 81 to close and to be held closed by a suitable clasp without utilizing the ends 76 of the bridge piece and so that this bridge piece may be slidably moved along walls 70 with the cover closed. It will be understood also that the dimensions of the receptacle may be such as will conform to the size of the bracelet requisite for encircling the wrist while avoiding a heavy or bulky structure. These dimensions, for example, may be similar to those of a wrist-watch. The receptacle also may be of curved form as to its bottom and side walls so as to conform to or be in parallel relation to the curve or arcuate circumferential extent of the bracelet. The receptacle as a whole forms a segmental portion of the annulus of the bracelet which provides a compact which may be carried in convenient position on the arm or wrist and beneath which, if desired, a space may be provided into which a handkerchief may be tucked. The slideable member, such as the member 27 in Figs. 4, 6 and 7 or the bridge piece 75 of Figs. 11-15, may be slidably supported on the annular part itself, such as the band 20, Fig. 4, or on the portions of the side walls 70 beneath the slot 79, Fig. 11, instead of on the segment which is exterior to the annular part. In such case the clip may be pressed upon the segment as it is drawn into the space between the segment and the annular part.

In Fig. 16 is shown an embodiment of the invention wherein the annular part 60 is constructed similarly to that of the bracelet of Figs. 12-15 with two sections 61 and 62 fitting together in the manner described in connection with Fig. 12. As in Fig. 12, the section 61 is provided with a plane wall 65 upon which is fastened by suitable means, such as riveting or brazing, the clip 90 which may be of spring material and biased so that the ball end 92 thereof moves toward or into contact with the wall 65 so as to hold a handkerchief placed beneath said ball end of the clip. In this embodiment of the invention, a cover 94 is hingedly supported at 95 at the left hand end of the annular wall 65. The cover is provided with a side wall 96 and end walls 97. The side of the cover opposite the side wall 96 is left open so that a handkerchief placed beneath the clip 90 may project through this open side and depend from the bracelet or lie generally parallel to the arm extended through the bracelet, that is, through the annulus formed by the section 61 and its wall 65 together with the section 62. If desired the opening in the cover may be formed in an end wall thereof, the clip

preferably being in a position at right angles to that shown in Fig. 16.

In Fig. 17 is shown a bracelet embodying another form of the invention in which two annular parts 100 and 101 are arranged side by side and supported in this relation with respect to each other by hinge 103 attached to each of these annular parts at one side thereof. The hinged arrangement of the parts 100, 101 permits separation of these parts so that a handkerchief may be placed between the adjacent edges thereof. Preferably these parts are provided with notches 104 and 105 formed therein adjacent each other so that the fold of the handkerchief may be inserted when the parts 100 and 101 are separated. When they are brought together again the edges of the notches bear on the fold of the handkerchief to hold it attached to the bracelet.

At the right hand side of the annular parts 100 and 101 a flat spring 107 is shown in Fig. 17 which is somewhat under tension when the parts 100 and 101 are in their closely adjacent relation. Upon separation of these parts for insertion of the handkerchief, the spring 107 is capable of being further stretched and when the parts are permitted to come together again, under the pull of the spring, the spring 107 holds them biased toward each other to hold the handkerchief between the edges of the notched portions of the annular parts 100 and 101.

For support of the hinge 103, the annular parts 100 and 101 may be formed with flattened bosses 108 which provide a planar face on each part upon which to fasten the hinge 103. Similarly at the right hand side of Fig. 17 bosses 109 may be formed for attachment and support of the flat spring 107. One end of this spring may be attached at the upper end of the boss 109 on annular part 100 and the other end of which may be attached at the lower end of the boss 109 on the annular part 101 or the ends of the spring may be attached at the adjacent edges of bosses 109 or other suitable straight portion of the annular parts.

Within the scope of the invention, the clip itself may be made of spring material and may be attached in various ways to the annular member or to the slideable member and this clip may be biased by its own spring quality or by means of an auxiliary spring, such as is shown in Figs. 1-15 inclusive, either toward or away from the cooperating part such as the annular part or the segmental member which is supported on the annular part. The direction of the bias will depend upon the form and the action of the part with which the spring is intended to cooperate. Particularly where the clip is biased away from the part with which it cooperates to hold the handkerchief, means such as have been described above are required to press the clip against its bias toward the cooperating part. When the clip is biased toward the cooperating part it may be lifted therefrom when inserting the handkerchief therebeneath.

The annular part may take other forms than that shown and described hereinabove to provide artistic design or convenience. Where the segmental member is shown, as in Figs. 4, 6 and 7, with open sides and connecting webs 23, these webs may be extended for the full length of the segment so as to close these sides, especially where the segment fully covers the space to be occupied by the clip and fold of the handkerchief. In such case the sliding member 27 may

be mounted on the internal face of the segment 25 in sliding relation thereto or the webs may extend from the annular member 20 toward but not quite to the segment 25 to provide a slot at each edge of the segment through which the sliding member 27 may extend for engagement with the segment.

In Fig. 17 if desired springs similar to spring 107 or of other suitable form may be provided at both bosses 108 and 109 or at other convenient circumferentially spaced points so that the parts 100 and 101 may be moved apart bodily rather than by hinging action, the springs serving to restore the parts to the clasping position. If required guides may be provided which engage the parts to hold them in generally parallel relation to each other.

In Fig. 18 is shown an adaptation of the invention to a belt such as may be worn about the waist. The belt comprises a flexible band or strap 120 of any suitable matter having attached at one end a buckle 122 of conventional design. The buckle shown in Fig. 18 is of the type in which the belt passes through a buckle frame 123 and is clamped under pull of the belt between the inner surface thereof and a knurled surface upon a member 125 hingedly supported in frame 123 and to which one end of the belt is attached. While this type of buckle has certain advantages hereinafter referred to, any of the types of buckle ordinarily used, especially in ladies' belts, may be adopted, such as those with a tongue for passing through holes in the opposite end of the belt or those in which the end of the belt passes reversely about cross bars and by friction thereon, aided by the friction of the material of the belt on itself, is held against slipping. Any of such conventional buckles may be chosen when, as in the preferred embodiment, the handkerchief-holding device 127 of the invention is attached to the belt so as to be positioned at a greater or less distance from the buckle so that the handkerchief may be carried at the side of the waist rather than directly in front of the body, where the buckle usually is worn.

The device 127 comprises a segment 129 attached by webs 131 to back plate 133 in a manner similar to the arrangement shown in Fig. 4. Upon the segment 129 a member 135 is slidably supported and carries spring piece 137 and clip 139. The spring piece 137 cooperates with the segment 129 to press clip 139 toward the back plate 133 when the member 135 is slidably moved along segment 129 to engage and to draw a portion of a handkerchief beneath the segment 129 in the same manner as described in connection with Fig. 4.

The plate 133, if desired, may be fastened by rivets or other suitable means to the fabric of belt 120 so as to positon the device 127 in the desired place at the waist, when the belt is worn, for convenience and style. In the preferred form shown in Fig. 18, connected to the back plate at each end thereof are straps 141 attached at the upper and lower edges of the plate and providing spaces through which the belt may be slipped, formed so that the straps 141 engage the belt and by friction hold the device 127 in any position in which it is set along the belt.

The device 127 of Fig. 18, if desired, may be attached to or constructed as part of the buckle 122. This may be done by fastening the back plate 133 to the front plate 124 of the buckle 122, for example by riveting, welding or brazing. To this end the buckle 122 may be made of sufficient

length to conform to the requisite length of the back plate 133. The buckle and the device 127 also may be constructed as one unit of suitable design for inserting and holding the belt while mounting the handkerchief-holding device so that the handkerchief may be inserted and removed, and may be held in an artistic manner when inserted in the device 127 as above disclosed in connection with the several other embodiments of the invention.

Various other changes in the form and details of the structure may be made without departing from the invention which is not to be deemed as limited otherwise than as indicated by the appended claims.

Within the scope of the invention other variations and combinations may be made and the bracelet may be made of various materials, such as metals and plastics, or of fabrics of different kinds which are suitable to provide the support for the clip to hold the handkerchief attached to the bracelet and preferably to provide the covering and concealment of the clip and its spring piece when the handkerchief is inserted beneath the clip and moved to the position more or less predetermined for holding the handkerchief with the decorated portion thereof depending from the bracelet.

We claim:

1. A bracelet comprising a part for extending about the arm, a part supported by said first part, said parts being arranged for movement slidably with respect to each other in a direction lengthwise of said first part, and means cooperating with at least one of said parts to attach a handkerchief to the bracelet and actuated when one of said parts is slidably moved relative to the other.

2. A bracelet comprising an annular part, and a part supported by and slidably circumferentially along said annular part, one of said parts having means adapted to engage a handkerchief to attach said handkerchief to said bracelet and actuated when one of said parts is slidably moved relative to the other.

3. A bracelet comprising an annular part, a part supported by said annular part, said parts being slidably movable relative to each other circumferentially of said annular part, a handkerchief-engaging clip carried by one of said parts and cooperating with the other of said parts as one of them is slidably moved relative to the other to bring said clip into holding engagement with said handkerchief.

4. A bracelet comprising an annular part, a member supported on and slidably movable circumferentially along said annular part, and a clip carried by said annular part exteriorly thereof for holding a handkerchief attached to said bracelet, said member having an extent circumferentially along said annular part and being spaced therefrom exteriorly thereof to form therewith a space within which a portion of said handkerchief held by said clip is drawn upon said sliding movement of said member relative to said annular part.

5. A bracelet comprising an annular part, a member supported on and slidably movable circumferentially of said annular part, and a clip carried by said member and cooperating with said annular part to hold a handkerchief attached to said bracelet upon sliding said member and clip to a predetermined position relative to said annular part.

6. A bracelet according to claim 5 which in-

cludes means to bias said clip out of handkerchief holding relation to said annular part, and means effective upon sliding movement of said member to press said clip into engagement with said handkerchief against its bias.

7. A bracelet comprising an annular part, a part supported by said annular part in spaced relation thereto exteriorly thereof and with its extent generally parallel circumferentially to said annular part, and a clip for engaging a handkerchief to attach said handkerchief to said bracelet, said clip being supported on said bracelet so as to be slidably circumferentially of the annular part between said annular part and said parallel part to draw the engaged handkerchief into the space between said parts upon said sliding movement of said clip.

8. A bracelet comprising an annular part, an arcuate part supported on said annular part in spaced relation thereto exteriorly thereof and with its arcuate extent generally parallel circumferentially to said annular part, said arcuate part being slidably movable circumferentially of said annular part, and a handkerchief-engaging clip carried by and positioned on said annular part exteriorly thereof so as to be within said space between said annular part and said arcuate part on sliding movement of said arcuate part relative to said annular part, and means cooperating with said annular part and said arcuate part to effect engagement of the handkerchief by said clip and to dispose the handkerchief within said space upon said sliding movement of said arcuate part relative to said annular part.

9. A bracelet comprising an annular part, a part fixedly supported on said annular part in spaced relation thereto exteriorly thereof and with its extent generally parallel circumferentially to a portion of said annular part, and a handkerchief-engaging clip supported on one of said parts and slidably circumferentially along said parts within the space therebetween, said clip being formed and arranged to press upon the exterior surface of said annular part, whereby the handkerchief inserted beneath the clip is drawn into said space upon such sliding movement of said clip.

10. A bracelet as defined in claim 9 in which said part fixedly supported on said annular part comprises a receptacle the bottom of which is spaced from said annular part to provide the space within which said clip is slidable, means attached to said clip and slidably supported on the side walls of said receptacle to provide said sliding movement of said clip, said means also providing latching means for a cover for said receptacle.

11. A bracelet as defined in claim 9 in which said annular part comprises a section of tubular form at its ends, and a section having two tongues spaced circumferentially of the annular part and respectively insertable in said tubular ends to complete the annular part.

12. A bracelet as defined in claim 8 in which said means cooperating with said annular part and said arcuate part comprises means to bias said clip against engagement of the handkerchief, said arcuate part being effective upon sliding movement thereof to enclose the handkerchief within said space and to actuate said clip for engaging the handkerchief.

13. A bracelet comprising an annular part, a part fixedly supported on said annular part in spaced relation thereto exteriorly thereof and with its extent generally parallel circumferen-

tially to a portion of said annular part, and a handkerchief-engaging clip supported on one of said parts and slidably circumferentially along said parts within the space therebetween, said clip being formed and arranged to press upon the surface of one of said parts, whereby the handkerchief inserted beneath the clip is drawn into said space upon such sliding movement of said clip.

14. A bracelet comprising an annular part for extending about the arm, a clip fastened to said annular part exteriorly thereof for engaging a handkerchief to attach the handkerchief to the bracelet, and a cover carried by the annular part for covering said clip and adapted to be movable to expose the clip for insertion of the handkerchief, said cover and annular part being so formed with respect to each other as to provide an opening through which a portion of the handkerchief may depend from said clip.

15. In an article of personal wear, the combination with a band for extending about a portion of the body, of a segmental member carried by said belt or band exteriorly thereof, and a handkerchief-engaging clip supported for sliding movement along said segmental member, and means cooperating with said segmental member upon sliding movement of said clip for actuating said clip to engage a handkerchief placed beneath the clip to attach the handkerchief to said band.

16. In an article of personal wear, the combination with a band for extending about a portion of the body, of a segmental member carried by said band, said segmental member having a segment generally parallel to the length of the band and spaced outwardly therefrom, a clip supported by said segmental member for sliding movement thereon lengthwise of the band so as to pass within the space between said segment and said band, and means cooperating with said clip and said segmental member for actuating said clip to engage a handkerchief upon such sliding movement of the clip and to draw a portion of the handkerchief within said space to attach said handkerchief to said band.

17. In an article of personal wear the combination with a band for extending about the body, of a part carried by said belt or band, means carried by said part and slidably movable relative thereto and biased to cooperate therewith upon such sliding movement for engaging a handkerchief to attach the handkerchief to said belt or band.

18. An article of personal wear comprising an annular part for extending about a portion of the body, and a part supported by said annular part in spaced relation thereto exteriorly thereof and with its extent generally parallel circumferentially to said annular part, and means cooperating with said parts for engaging a handkerchief or the like, said means and at least one of said parts being relatively movable in a direction parallel to the circumferential extent of said annular part to bring at least a portion of said handkerchief within the space between the annular part and said parallel part.

19. A bracelet comprising an annular part for extending about the arm, a wall supported on said annular part so as to extend generally parallel to the circumferential extent thereof and generally parallel to the surface of the arm when the bracelet is in position thereon, said wall being spaced outwardly from said annular part to form therewith a space for receiving a handkerchief, walls upstanding from said spaced wall outwardly

with respect thereto to form therewith a receptacle, and a cover supported by said upstanding walls to close the receptacle so as to provide a compact carried by the bracelet.

SIDNEY R. HARRIS.
GREGORY ASHMAN.
